4 Claims. (Cl. 330—3)

This invention relates to circuits for matching high impedance signal sources to low impedance loads and is concerned with cathode-follower and emitter-follower circuits.

The voltage gain of a simple cathode follower can be made to approach unity, which is desirable from the point of view of reducing the effective input capacity, provided that the nett cathode load is of high impedance. A low output impedance can be obtained by using a "White cathode follower" but, in its normal form the low output impedance of the white cathode follower does not extend down to zero frequency because of the A.C. coupling.

Emitter followers are also used to match high impedance signal sources to low impedance loads. The output resistance is approximately

$$r_e + \frac{r_s}{\beta}$$

where r_e is the emitter resistance under common-base conditions, β is the common emitter current gain and r_s is the resistance of the signal source. The output resistance is lower when two or more emitter followers are used in cascade but it can never be less than the r_e of the last stage, which is usually in the region of a few ohms, unless power transistors are used with a large emitter current.

The present invention seeks to achieve a gain closely approaching unity and a low output impedance from zero up to a very high frequency.

According to the present invention a circuit for matching a high impedance signal source to a low impedance load comprises a cathode-follower or an emitter follower with an input connection to its control grid or base respectively, a first transistor having its emitter connected to the cathode or emitter of the follower such that any change in cathode or emitter current of the follower appears as a change of equal magnitude in the emitter current of the first transistor, a collector load for the first transistor, connections between the collector of the first transistor and the base of a second transistor and between the emitter of the second transistor and the base of the first transistor such that any change in the collector current of the first transistor is fed back to oppose the change, and an output connection from the emitter of the second transistor.

The transistors referred to as the first and second transistors are, of course, additional to the emitter follower transistor if one is used. They may be p-n-p transistors, and the collector load of the first transistor may be a resistor or a further transistor connected in a constant-current circuit.

Alternatively the first and second transistors may be n-p-n transistors, and the cathode load may be a further transistor connected in a constant-current circuit.

Constant-voltage means may be connected between the output and the valve anode to maintain constant the anode-to-cathode voltage.

To enable the nature of the present invention and in what manner it is to be performed to be more readily understood, attention is directed by way of example to the accompanying drawings, wherein FIGS. 1, 2 and 3 are circuit diagrams of cathode-follower circuits embody-

2

ing the invention and FIGS. 4 to 8 are circuit diagrams of emitter-follower circuits embodying the invention.

Referring firstly to FIG. 1, the cathode current of a valve V1 flows to the emitter of a first p-n-p transistor J2 and thence through the collector load R1. Any change in the collector current of J2 is fed to the base of a second p-n-p transistor J3 and fed back from J3 emitter to J2 base in a sense to oppose the change. The effect is to maintain the collector current of J2, and hence the cathode current of V1, substantially constant. Hence the emitter-base voltage of J2 and the grid-cathode voltage of V1 remain constant and the output from J3 emitter closely follows the input to the grid of V1. The transistor J3 drives the output load RL. The function of R2 is to provide current for positive excursions of the output.

It can be shown, to a good approximation, that

$$\frac{V_{in}}{V_{out}} = 1 + \frac{1}{\mu} + \left(\frac{1}{g} + R_e \right) \left(\frac{1}{R1} + \frac{1}{\beta R} \right) \quad (1)$$

20 where

V_{in} =input signal voltage

V_{out} =output voltage

μ =amplification factor of V1

25 g =mutual conductance of V1

R_e =emitter resistance of J2

RL =load resistance

β =current gain of J3, and

$$R = \frac{R2RL}{R2+RL}$$

30 Consider first the simple case where R2 and RL are both larger than R1 so that $\beta R \gg R1$. Clearly R2 can be made large when the load resistance RL is large. In this case:

$$\frac{V_{in}}{V_{out}} = 1 + \frac{1}{\mu} + \left(\frac{1}{g} + R_e \right) \cdot \frac{1}{R1} \quad (2)$$

35 If V1 has $g=10$ ma./v., $\mu=50$ at a cathode current of 10 ma., the value of R1 will be 3K ohms assuming the input to be at about zero volts.

Then

$$\frac{V_{in}}{V_{out}} \text{ approx.} = 1 + \frac{8}{150} \quad (3)$$

40 Although the circuit of FIG. 1 shows no improvement in terms of gain over an ordinary cathode follower with a cathode load of 3K ohms, because of its low output impedance it is more useful when the load resistance has a low value. Assume $RL=100$ ohms and $\beta=50$. For moderately small signals the value of R2 will be much greater than RL (because R2 is returned to 150 v.), so it is possible to put $R=100$ ohm in Equation 1 and obtain

$$\frac{V_{in}}{V_{out}} \text{ approx.} = 1 + \frac{11}{150} \quad (4)$$

45 Comparing results (3) and (4) it is seen that the loss of gain when the load resistance is reduced from a large value to 100 ohms is about 2%. In the case of a conventional cathode follower using the same valve the loss of gain would be about 50%. A "White cathode follower" can give a performance similar to that of the circuit of FIG. 1, but not for very low signal frequencies except when elaborate D.C. coupling is used.

50 An improvement can be obtained if we make R1 very large by using a constant-current load in place of R1, since the whole of any change in J2 collector current is then fed to the base of J3. Equation 1 then reduces to:

$$\frac{V_{in}}{V_{out}} = 1 + \frac{1}{\mu} + \left(\frac{1}{g} + R_e \right) \frac{1}{\beta R} \quad (5)$$

The output resistance R_o is then given by

$$R_o = \left(\frac{1}{g} + R_e \right) \frac{\mu}{\beta(\mu-1)} \quad (6)$$

Using readily available valves and transistors the output resistance will be of the order of 1 ohm and the gain will be

$$\frac{\mu}{\mu+1}$$

for moderately large load resistances.

The load current for positive signals is obtained by a corresponding reduction in emitter current of J3; negative signals increase the emitter current. The transistor J3 should therefore have adequate power handling capacity for large excursions of load current. The output resistance and voltage gain remain constant from zero frequency up to a frequency at which J2 or J3 lose current gain. Typical component values in the circuit of FIG. 1 are $RL=1K$ ohms, $R1=3.3K$ ohms and $R2=30K$ ohms. $E1$ may be 150 volts positive and $E2$ may be 30 volts negative.

It is possible to obtain a voltage gain almost equal to unity as well as a low output resistance by using the improved circuit of FIG. 2. Here a constant-current collector load for J2 is provided by the n-p-n transistor J4, whose emitter current is defined by the potentiometer R5, R6 and the emitter resistor R7. In addition, the output voltage variations are fed to the anode of V1 through the gas discharge diode V2, thereby maintaining constant the anode-cathode voltage of V1 and hence the anode current. Zener diodes of the appropriate voltage can be used in place of V2 with advantage, because of their lower impedance. With these improvements Equation 1 simplifies to

$$\frac{V_{in}}{V_{out}} \text{ approx.} = 1 + \left(\frac{1}{g} + R_e \right) \frac{1}{\beta R} \quad (7)$$

where R is the value of the load resistance in parallel with the resistance $R4$ which is in series with the anode of V1. The output resistance R_o is given by

$$R_o \text{ approx.} = \left(\frac{1}{g} + R_e \right) \frac{1}{\beta} \quad (8)$$

In general it is possible to achieve an output resistance of about 1 ohm, and if the load resistance is much greater than R_o the gain is almost unity as seen from (7). A major advantage of this circuit is that the negative supply voltage need only be slightly greater than the maximum negative excursion of the signal, because the collector of J4 need only be a few volts more positive than this supply. The emitter current of J3 for positive output excursions is supplied via V2. Typical component values in the circuit of FIG. 2 are $R4=3.3K$ ohms, $R7=220$ ohms, $R5=2.2K$ ohms, $R6=15K$ ohms. V1 is an RCA Nuvistor 6CW4 and V2 has a running voltage of about 100 v.

FIG. 3 shows a modification of the circuit of FIG. 2 for use with large positive excursions of load current. The p-n-p transistors J2, J3 are replaced by n-p-n transistors J2', J3'. V1 has a constant-current cathode load comprising an n-p-n transistor J5 and associated resistors R12, R13 and R14. Any change in the cathode current of V1 therefore appears as a change of equal magnitude in the opposite sense in the emitter current of J2', whose collector current is fed back to the base or J2' via J3' as before to oppose the change. A constant-current load for the collector of J2' is unnecessary, since the positive supply voltage E1 is large (say 150 v.) and enables R8 to be large. Typical component values in the circuit of FIG. 3 are $R4=3.3K$ ohms, $R8=33K$ ohms, $R9=1.5K$ ohms, $R12=220$ ohms, $R13=2.2K$ ohms, $R14=15K$ ohms. V1 and V2 are as in FIG. 2. E5 may be 15 volts positive and E4 15 volts negative.

In some instances the transistor J2 or J2' may require a larger collector voltage than that provided in the cir-

cuits shown. This can be achieved by inserting a Zener diode of suitable voltage in series with the emitter of the output transistor J3 or J3'.

In small-signal applications the circuits of FIGS. 2 and 3 can be particularly useful because of the extremely low input capacitance that can be achieved. Since the anode and cathode of V1 follow the input signal, the grid-anode and grid-cathode capacitances are effectively reduced by a factor of about R/R_o . The same reduction in the capacitance between the input and various shields can be obtained by connecting these shields to the output. In practice it may be possible to reduce the input capacitance to a value considerably smaller than 1 p F. even when the load resistance at the output is as small as 100 ohms.

When a large capacitance is placed across the output there will tend to be an overswing due to charge storage when handling fast transients. The use of the RC combination R15, C2 (FIG. 2) or R15', C2' (FIG. 3) shown will prevent this overswing, by reducing the loop gain at high frequencies, R15 and R15' being in parallel with the collector loads of J2 and J2' respectively. It has been found preferably, however, to replace these overswing-prevention circuits C2, R15 and C2', R15' by CR integrating circuits connected in series with the input grid, in an analogous manner to that shown in FIGS. 5-7 which are hereinafter described. Suitable values for the cathode-follower circuits are $C=0.1$ pf., $R=100K$ ohms. When the capacitative load is extremely large it is desirable to use a resistor (not shown) in series with the output in order to limit the peak currents in the transistors.

A basic emitter-follower circuit of the invention is shown in FIG. 4 in which an n-p-n transistor J1 connected as an emitter-follower takes the place of the valve V1. The current through both the transistor J1 and the p-n-p transistor J2 is approximately $E2/R1$ and that through the p-n-p transistor J3 is approximately $E1/R2$ (neglecting the current through the load RL) under static conditions. Most of the load current flows through J3. When an input signal voltage is applied of J1 base, the current through J1 and J2 tends to change but this produces a much larger change in the emitter current of J3 with the result that the final change in the current through J1 and J2 is considerably reduced. If V_{in} is the change in input voltage and V_{out} is the change in output voltage it can be shown that to a good approximation

$$\frac{V_{in}}{V_{out}} = 1 + (r_{e1} + r_{e2}) \left[\frac{1}{\beta_3 R'} + \frac{R' + r_{e3}}{R_1 R'} \right] \quad (9)$$

where

r_{e1} = emitter output resistance of J1 with common-base connection.

r_{e2} = emitter output resistance of J2 with common-base connection.

r_{e3} = emitter output resistance of J3 with common-base connection.

β_3 = common emitter current gain of J3, and

$$R' = \frac{R_1 R L}{R_1 + R L}$$

If

$$r_{e3} \ll R' \ll \frac{R_1}{\beta_3}$$

then

$$\frac{V_{in}}{V_{out}} = 1 + \frac{r_{e1} + r_{e2}}{\beta_3 R'} \quad (10)$$

It can be shown that, with the above approximations, the input resistance is $\beta_1 \beta_3 R'$ shunted by $r_{b1} \beta_3$ where β_1 is the common emitter current gain and r_{b1} is the collector-base resistance of J1. The output resistance is

$$\frac{R_s}{\beta_1 \beta_3}$$

where R_s is the output resistance of the signal source. Thus when the load resistance is 100 ohms the input resistance will be 250K ohms shunted by r_{b1c} , assuming $\beta_1 = \beta_3 = 50$. The ratio

$$\frac{V_{in}}{V_{out}}$$

will be 1.004 assuming $r_{e1} = r_{e2} = 10$ ohm. When the load resistance is 10 ohms the ratio

$$\frac{V_{in}}{V_{out}}$$

will be 1.04 and the input resistance will be 25K ohms using the above transistor parameters.

An improved form of the circuit which is particularly useful for small signal conditions and driving larger load resistances and which satisfies the approximations

$$r_{e3} \ll R \ll \frac{R_1}{\beta_3}$$

is shown in FIG. 5. The current through J1 and J2 is fixed by a constant-current load which can take any of the well known forms. In the present embodiment this load is provided by the n-p-n transistor J4 whose emitter current is defined by the potentiometer R5, R6 and the emitter resistor R7. The Zener diode D ensures that the voltage between base and emitter of J1 remains constant so that r_{b1c} of the first transistor no longer becomes an appreciable component of the input resistance. The current through R4 in excess of that through J1 flows through J3. The integrating time-constant R3C1 ensures that the system remains stable, it being necessary also to use as J2 as a transistor with a cut-off frequency much higher than that of J1 and J3. With J1 and J3 having cut-off frequencies of about 1 or 2 mc./s. it is desirable to use as J2 a transistor with a cut-off frequency in excess of 50 mc./s. Typical values of R3 and C1 will then be 10K ohms and 47 pf. respectively. The addition of R3 and C1 does not appreciably affect the input impedance, C1 being very much smaller than the input capacity of the transistor. With this circuit, input resistances much greater than 1M ohm and

$$\frac{V_{in}}{V_{out}} < 1.001$$

can be obtained when the load resistance is 1K ohm, using only a few milliamperes in the transistors. The output resistance will be less than 1 ohm.

FIG. 6 shows a further embodiment (analogous to the arrangement shown in FIG. 3) in which J2' is an n-p-n transistor. Constant-current loads I1 and I2 are preferably provided for J1 and J2' respectively, but resistors may be adequate in some applications. This circuit has two advantageous characteristics. Firstly, when the input voltage at the base of J1 is zero the output voltage is zero since the emitter-base potentials of J1 and J2' are in opposite directions and so substantially cancel out; hence the load current is zero. Secondly, because these potentials are in opposite directions, variations therein due to temperature changes similarly cancel out, so reducing drift. By contrast the emitter-base potentials of J1 and J2 in FIGS. 4 and 5 are in the same direction, so that when the input voltage is zero the output voltage is the sum of the emitter-base potentials of the two transistors below zero, i.e., about -0.4 v., and some current flows through the load; variations due to temperature changes are similarly additive, giving rise to drifts.

Another form of the circuit which is particularly useful for driving a low value of load resistance with peak voltages approaching the values of the power supply lines is shown in FIG. 7. In this arrangement the collector of J1 is taken to the base of a p-n-p transistor J4' whose emitter is connected to the positive supply line and whose collector is connected to the output. In FIGS. 4 and 5 the

current available for the load during large positive voltage excursions of the output is limited by R2 and R4 respectively. In the circuit of FIG. 7 the collector of J4' can rise to within 0.5 v. of the positive supply line +E1 without limiting the current flowing through J4' to the load. If J3 and J4' have equal values of current gain the base current in each will be half that supplied by the constant-current source I3. In general the base currents of the output transistors J3, J4' will be inversely proportional to their current gains. If the load resistance is extremely small the current in J3 will be greater than that in J4' when the input is at earth potential, since the emitter of J3 is slightly negative, as mentioned above, and some current will flow through the load. This circuit can be used to drive loads such as loudspeakers directly.

FIG. 8 shows a circuit for use where supply lines of both polarities are not available. One end of the load RL (which might be a loudspeaker) is connected to the output of a circuit as in FIG. 7 comprising J1, J2, J3, and J4'. The other end of RL is connected to the output of an identical reference circuit comprising J11, J22, J33 and J44'. The input voltage V_{in} is applied between the bases of J1 and J11, whose static potential is determined by a tapping on a common potential divider R10, R11 connected to J11 base.

The main virtues of the circuits are high input impedance, low output impedance and a gain very close to unit. All the above characteristics are maintained from D.C. up to a frequency whose limit is set purely by the cut-off frequencies of the transistors.

In all the described circuits the n-p-n transistor J1 can be replaced by a p-n-p type if corresponding modifications are made to the remainder of the circuit. For example in FIG. 4, J2 and J3 would then become n-p-n type transistors.

I claim:

1. A circuit for matching a high impedance signal source to a low impedance load comprising a thermionic valve which has an anode, a cathode and a control grid and which is connected as a cathode-follower, an input connection to said control grid, first and second supply lines, a connection from said anode to the first supply line, a first junction transistor having its emitter connected to said cathode such that any change in the cathode current of said valve appears as a change of equal magnitude in the emitter current of the first transistor, a resistive collector load for the first transistor connected between the collector electrode of the first transistor and the second supply line, a second junction transistor, connections between the collector of the first transistor and the base of the second transistor and between the emitter of the second transistor and the base of the first transistor such that any change in the collector current of the first transistor is fed back to oppose the change, a connection between the collector of the second transistor and the second supply line, a resistive connection between the base of the first transistor and the first supply line, and an output connection from the emitter of the second transistor.

2. A circuit for matching a high impedance signal source to a low impedance load comprising a thermionic valve which has an anode, a cathode and a control grid and which is connected as a cathode-follower, an input connection to said control grid, first and second supply lines, a resistive connection from said anode to the first supply line, a first junction transistor having its emitter connected to said cathode such that any change in the cathode current of said valve appears as a change of equal magnitude in the emitter current of the first transistor, a second junction transistor, connections between the collector of the first transistor and the base of the second transistor and between the emitter of the second transistor and the base of the first transistor such that any change in the collector current of the first transistor is fed back to oppose the change, a constant-current network formed by a third junction transistor the emitter-collector path of

which is connected in series with resistance between said cathode and the second supply line, and the base of which is connected to a point on a potentiometer connected between the second supply line and earth, a constant-voltage device connected between anode and the base of the first transistor such that the anode current of said valve is maintained substantially constant, and an output connection from the emitter of the second transistor.

3. A circuit for matching a high impedance signal source to a low impedance load comprising a first junction transistor which is connected as an emitter-follower, an input connection to the base of the first transistor, first and second supply lines, a connection from the collector of the first transistor to the first supply line, a second transistor having its emitter connected to the emitter of the first transistor such that any change in the emitter current of the first transistor appears as a change of equal magnitude in the emitter current of the second transistor, a resistive collector load for the second transistor connected between the collector electrode of the second transistor and the second supply line, a third junction transistor, connections between the collector of the second transistor and the base of the third transistor and between the emitter of the third transistor and the base of the second transistor such that any change in the collector current of the second transistor is fed back to oppose the change, a connection between the collector of the third transistor and the second supply line, a resistive connection between the base of the second transistor and the first supply line, and

an output connection from the emitter of the second transistor.

4. A circuit for matching a high impedance signal source to a low impedance load comprising a first junction transistor which is connected as an emitter-follower, an input connection to the base of the first transistor, first and second supply lines, a resistive connection from the collector of the first transistor to the first supply line, a second transistor having its emitter connected to the emitter of the first transistor such that any change in the emitter current of the first transistor appears as a change of equal magnitude in the emitter current of the second transistor, a third junction transistor, connections between the collector of the second transistor and the base of the third transistor and between the emitter of the third transistor and the base of the second transistor such that any change in the collector current of the second transistor is fed back to oppose the change, a constant-current network formed by a fourth junction transistor the emitter-collector path of which is connected in series with resistance between the collector of the second transistor and the second supply line, and the base of which is connected to a point on a potentiometer connected between the second supply line and earth, a constant-voltage device connected between said anode and the base of the second transistor such that the collector current of the first transistor is maintained substantially constant, and an output connection from the emitter of the third transistor.
